UNITED STATES PATENT OFFICE.

JOHN W. BOZEMAN, OF BALTIMORE, MARYLAND, AND JOHN T. JONES, OF MADRAS, GEORGIA.

TANK-FILLING VALVE.

1,368,884.

Specification of Letters Patent. Patented Feb. 15, 1921.

Application filed October 9, 1919. Serial No. 329,510,

To all whom it may concern:

Be it known that we, JOHN W. BOZEMAN, a citizen of the United States, residing at Baltimore, Maryland, and JOHN T. JONES, 5 a citizen of the United States, residing at Madras, in the county of Coweta and State of Georgia, have invented certain new and useful Improvements in Tank-Filling Valves; and we do declare the following to 10 be a full, clear, and exact description of the invention, such as will enable others skilled in the art to which it appertains to make and use the same.

This invention relates to improvements in 15 tank filling valves and more particularly to those intended primarily for use in connection with flush tanks.

One object of our invention is to provide a tank filling valve having a renewable 20 valve member to be replaced when worn, and to make novel provision for preventing the escape of water while renewing said valve member, thus overcoming the necessity of cutting off the flow of water through 25 the entire supply line, as is now usually necessary.

Another object is to provide a valve of the character set forth, in which the auxiliary 30 valve closes automatically when a portion 35 of the main float controlled valve is removed for renewing a worn valve member.

A still further object is to provide a valve 35 of the type in question, which will be simple and inexpensive, easy to install, approximately silent in operation, and one in which wearing of the valve member is equalized by a novel mounting of the bell or valve body which carries said member.

With the foregoing in view, the invention 40 resides in the novel construction and arrangement of parts hereinafter described and claimed, the descriptive matter being supplemented by the accompanying drawings.

45 Figure 1 of the drawings is a side elevation of the valve applied to a flush tank.

Fig. 2 is a vertical section with parts in elevation, showing the position of parts when the tank is completely filled.

50 Fig. 3 is a vertical section illustrating the

relation of parts when the valve is open for filling the tank.

Fig. 4 is a view similar to Fig. 2, but showing the manner in which the supplemental valve prevents the escape of water 55 when renewing the valve member or gasket of the float controlled valve.

Fig. 5 is a horizontal section on the plane of the line 5—5 of Fig. 2.

Fig. 6 is a side elevation of the hollow 60 passage member, a portion of said member being in section.

Fig. 7 is a vertical section partly in elevation, of the main valve carrying body or bell. 65

In the drawings, wherein for purposes of illustration, we have shown the preferred form of our invention, the numeral 1 designates a hollow cylindrical passage member adapted to pass through the bottom 2 of a 70 flush tank, the lower end of said passage member being provided with a suitable coupling 3 for attaching the water supply pipe 4. Any suitable means could be employed for securing the passage member 1 in place, 75 but it is preferably provided with an integral collar 5 to rest on the tank bottom, and with a clamping nut 6.

The upper end of the passage member 1 is provided with a valve seat with which a 80 valve member 7 coacts, said member being carried by a downwardly closing body 8. The valve member 7 is preferably in the form of a gasket of leather or other suitable material; said gasket is received in a socket 85 9 in the upper end of the valve carrying body 8, and a plug 10 is threaded into said socket, against said gasket to retain the latter in place. The valve carrying body 8 is provided with a suitable opening 11 exposing 90 the lower surface of the valve member or gasket 7 for proper presentation to its seat, and in the preferred embodiment of our device, we construct said valve carrying body in the form of a bell whose wall 12 is 95 loosely slidable and rotatable on the upper end portion of the passage member 1, being loosely guided by suitable lugs or the like 13. When the valve member 7 is unseated, the water discharges into the bell and 100

travels from the latter between the wall 12 and the passage member 1, and it has been found that this produces practically no noise.

5 Any adequate means could be employed for operating the member 8, but when this member is in the form of a bell as shown, its wall 12 is preferably provided with spaced circumferential shoulders 14 between 10 which rockers 15 on a yoke 16 are received, said yoke straddling the wall, being pivoted at one end, and operatively connected at its other end with a float controlled swinging arm 17. The yoke is preferably pivoted to 15 an arm 18 integral with the collar 5, while a similar arm 19 is provided for mounting the arm 17. By loosely positioning the entire valve carrying body 8 on the passage member 1 and associating the annular shoulders 14 with the rockers 15 in the manner disclosed, there is nothing to hinder slight rotary movement of said valve carrying body when the valve is in operation and consequently the valve member 7 will be 20 evenly worn.

25 Within the passage member 1 is a second valve seat with which an outwardly closing, pressure operated ball 20 or other suitable valve coacts to prevent the discharge of 30 water from said passage member while renewing the valve member 7. The valve carrying body 8 however, is provided with means for normally holding valve 20 against closing, and we prefer to embody such means 35 in the form of a stem 21 carried by the retaining plug 10. When the valve opens for filling the tank, the stem 21 holds the valve 20 against closing, but as soon as the plug 10 is partially removed, said stem permits 40 the valve in question to close under the pressure of the water, as seen in Fig. 4.

45 The seats for both valves 7 and 20 are preferably formed by the ends of a double ended cylindrical seat member 22 removably carried in the delivery end of the passage member 1. A sleeve nut 23 may be provided for retaining the seat member 22 in place and we prefer that a gasket 24 shall be interposed between the lower end of said member 50 and a shoulder 25 on the interior of the member 1. In some instances, this gasket might be of such proportions as to coact with the ball 20, but we have found that no yielding seat is necessary for said ball if the 55 latter is formed of fiber or other suitable material and the seat member constructed of porcelain or other appropriate material.

60 The stem 21 is preferably threaded into the retainer or plug 10 as seen at 26, and is provided with a collar or the like 27 contacting with the lower side of the gasket 7, whereby to clamp the latter against the bottom of said retainer or plug. The threads 26 permit relative adjustment between the parts

10 and 21 and thus gaskets 7 of different 65 thicknesses may be used.

Any appropriate means may be employed for retaining the ball valve 20 in the passage member 1, and for illustrative purposes we have shown a perforated partition 28 across 70 said passage member. This partition prevents excessive descent of the valve, but allows free passage of water through the device.

75 Our improved filling valve may be installed quickly and easily and adjusted for closing at the proper water level, in the usual way, that is by bending the arm 17. When properly installed, emptying of the tank opens the valve as seen in Fig. 3, and 80 on restoring of the water level the gasket 7 tightly seats upon the upper end of the seat member 22, thus cutting off the supply of water as illustrated in Fig. 2. Under the normal working of the valve, the stem 21 85 prevents closing of the valve 20, but whenever the retainer or plug 10 is removed for renewing the gasket 7, said valve is closed by the water pressure as shown in Fig. 4, thus 90 eliminating the necessity of turning off the supply of water at some point along the supply pipe 4. The device is practically silent in operation, and although the gasket 7 must be renewed from time to time, this 95 gasket has a much longer life than usual, since it moves in a true, vertical direction to and from its seat and is allowed to turn on said seat thereby equalizing wear.

100 Since probably the best results may be obtained from the several details disclosed, they may well be followed, but within the scope of the invention as claimed, numerous minor changes may well be made.

We claim:

105 1. A tank filling valve, comprising a passage member having a valve seat at its delivery end, a float actuated sleeve slidable loosely on said end of said passage member, the outer end of said sleeve having a threaded opening provided at its inner end with an annular internal shoulder, a valve disk bearing on said shoulder, a plug threaded in 110 said opening and securing said disk in place, a check valve in said passage, and a stem carried by and removable with said plug, 115 said stem extending into said passage member and serving to hold said check valve open until said plug is removed to renew said valve disk.

120 2. A tank filling valve, comprising a passage member internally threaded at its delivery end and provided with an internal annular shoulder at the inner end of the threaded portion, a tubular valve seat in 125 said delivery end of the passage member provided with an external annular shoulder, a ring nut surrounding said valve seat and coacting with said internal and external

shoulders to clamp said seat in place, a float actuated sleeve slidable loosely on the passage member and having a closed outer end provided with a valve disk coacting with 5 the outer end of said seat, a removable plug securing said valve disk in place, a ball check valve in said passage member for coaction with the inner end of said seat, and

an inwardly extending stem carried by said plug and preventing closing of said check 10 valve until said plug is removed to renew said valve disk.

In testimony whereof we have hereunto set our hands.

JOHN W. BOZEMAN.
JOHN T. JONES.
